UNITED STATES PATENT OFFICE.

WARREN O. LYNCH, OF BERKELEY, CALIFORNIA.

STIFFENER FOR FOLDING BOOKS.

1,423,129.

Specification of Letters Patent.

Patented July 18, 1922.

Application filed October 15, 1921. Serial No. 507,831.

To all whom it may concern:

Be it known that I, WARREN O. LYNCH, a citizen of the United States, and a resident of Berkeley, county of Alameda, and 5 State of California, have invented a new and useful Stiffener for Folding Books, of which the following is a specification.

The present invention relates to stiffeners for folding books and its principal object is 10 to provide a stiffener for folding check books as now commonly used and furnished by banks to their clients. It is well known that the check books now commonly used usually comprise, besides the detachable checks to 15 be torn out of the books, a stub for each blank check which is used for making a memorandum of the money withdrawn. Check books of this character are usually 20 rectangular in shape and adapted to be folded along a central line running parallel to the edge along which the book is bound. In using this book it becomes necessary to unfold the same but ordinarily the crease caused in each check by folding the book 25 extends directly through that portion of the check on which most of the writing is to be done, and the unfolded check has a tendency to bend along this crease which makes it very inconvenient for the operator to write 30 the check, especially if he has no solid foundation on which to lay the book.

It is the object of my invention to provide a convenient, economical and simple means by which the checks can be flattened so that 35 the crease formed by the folding disappears altogether and the check may be written on without any difficulty.

In the accompanying drawing I show the preferred form of my invention in connection with a check book, it being understood 40 that I do not wish to confine myself to check books as such but claim the invention with reference to any other books of similar form and similarly used. In the drawing, Figure 45 1 represents a perspective view of a check book provided with my stiffener in its unfolded condition; Figure 2 a folded check book having my stiffener attached thereto; Figure 3 a plan view of my stiffener illustrated by itself, and Figure 4 a cross section through the same along line 4—4 of 50 Figure 3.

The check book (1) comprises a plurality of stubs (2) and blank checks (3) bound 55 into book form and enclosed in the case (4). When the book is not in use the blank checks

(3) can be folded over so that the extreme edges of the same lie against the opposite edge along which the book is bound and the case (4) can be folded around the blank 60 checks in such a manner that its extreme edge (6) lies underneath the flap (7) and is adapted to be secured underneath the same by means of the button (8). Thus the folding of the book reduces its lateral extension 65 by about one half and it can be conveniently carried in the pocket. My stiffener (9), which is shown in detail in Figures 3 and 4, comprises an ordinary plate (11) of rectangular form having two flanges (12) which 70 are bent inwardly as shown at (14). The length of the plate (9) depends upon the length of the check book and should ordinarily equal about one half of the same. In width the plate is co-extensive with the 75 width of the check book so that the latter may be received in the channel-shaped grooves formed by the flanges (12). The latter flanges are provided at their ends with projections (16) which serve to insure a 80 better contact between the check book and the flanges.

To use my stiffener I only need to slip the same on the unfolded check book, slide the same to the extreme left when it is desired to close the check book, and slide the same to the right when the check book is unfolded and it is desired to use the same. When unfolded and used the check book and my attachment look like the illustration 90 in Figure 1, that is, a perfectly smooth surface is provided on which the operator may conveniently write.

I claim:

A stiffener for a folding book of the character described adapted to stiffen the same in its folded and in its unfolded condition comprising a stiffening plate substantially co-extensive with the folded book having flanges thereon adapted to slidably engage 95 the upper and lower edges of the body portion of the book and to be slid along the said edges when the book is unfolded so as to stiffen the creased portion of the book, a large central portion of the flanges being 100 cut away so as to fully disclose the reading matter on the check while the remaining projections extending from the ends of the flanges insure a firm contact between the plate and the book.

WARREN O. LYNCH.
